BOAT HOIST CAM LINKAGE

Everett A. Johnson, 15 S. Prospect Ave.,
Park Ridge, Ill. 60068

Filed Jan. 2, 1973, Ser. No. 320,556

Term of patent 14 years

Int. Cl. D12—05

U.S. Cl. D12—60

FIG. 1 is a face view of a boat hoist cam linkage embodying my new design.

FIG. 2 is a rear view of the boat hoist cam linkage of FIG. 1.

FIG. 3 is a top edge view of the boat hoist cam linkage shown in FIG. 1 and FIG. 2.

FIG. 4 is a bottom edge view of the boat hoist cam linkage shown in FIG. 1 and FIG. 2.

FIG. 5 is a section taken along 5—5 in FIG. 1.

The broken line showing of the clevis in the drawings illustrate the environment.

I claim:

The ornamental design for a boat hoist cam linkage, as shown and described.
